UNITED STATES PATENT OFFICE.

OTTO B. MACK, OF DES MOINES, IOWA, ASSIGNOR TO ALL-WEATHER SPARK PLUG COMPANY, OF DES MOINES, IOWA, A CORPORATION OF ARIZONA.

SPARK-PLUG.

1,227,470.

Specification of Letters Patent.

Patented May 22, 1917.

Application filed November 22, 1915. Serial No. 62,730.

To all whom it may concern:

Be it known that I, Otto B. Mack, citizen of the United States of America, and resident of Des Moines, Polk county, Iowa, have invented a new and useful Spark-Plug, of which the following is a specification.

The object of this invention is to provide an improved construction for spark plugs 10 of internal combustion engines whereby means is provided for heating the fuel gas at and adjacent the point of ignition, and also for removing carbon deposits in the spark plug.

15 A further object of this invention is to introduce a resistance coil in the spark plug through which the current is passed for the purpose of heating the fuel gas in and adjacent to the spark plug and for the further purpose of removing deposits of carbon and preventing undue accumulations thereof in the spark plug; thereby facilitating the operation of firing and increasing the power of the engine.

25 A further object of this invention is to provide an improved method of mounting the resistance coil relative to the porcelain barrel.

30 A further object of this invention is to provide a device of this kind which shall be simple and inexpensive of construction.

My invention consists in the construction, arrangement and combination of elements hereinafter set forth, pointed out in my 35 claim and illustrated by the accompanying drawing, in which—

The view is a central section of a spark plug constructed according to my invention.

In the construction of the device as shown 40 the numeral 10 designates the metallic shell of the spark plug, and 11 the insulating barrel, of porcelain or other suitable material, suitably mounted therein in a common manner and secured by a nut 12 screwed 45 into the outer end of the shell, a washer 13 being interposed between the adjacent shoulders of the shell and porcelain barrel. One of the electrodes, 14, is mounted in and lengthwise of the porcelain barrel 11 and 50 projects slightly below the lower end thereof to provide one of the sparking points. The porcelain barrel 11 preferably is constructed with a cylindrical central portion fitting snugly within the interior of the shell 10; with an upper tapered or frusto-

conical portion projecting through the nut 12 and materially above the top of the shell; and with a lower tapered portion projecting downwardly within and approximately from the bottom of the shell, and spaced 60 from the inner walls thereof. The barrel 11 also is formed with an annular shoulder or offset 15 at the upper end of the tapered lower portion, and adjacent the central cylindrical portion.

65 A coil 16, of high resisting qualities, is coiled around the tapered lower end portion of the porcelain barrel 11 within the chamber of the shell 10, and the lower end of said coil projects slightly below the lower 70 end of said shell, encircles (preferably but once) the projecting lower end of the electrode 14, and then turns laterally and is attached to the lower end of the shell 10, through which it is grounded. A channel 75 17 is formed in the upper portion of the porcelain barrel 11 and has its initial end in the shoulder or offset 15, leads upwardly in a straight line therefrom, and emerges from the tapered upper part of the barrel at a 80 point above the upper plane of the nut 12. The upper part of the coil 16 consists of a straight portion of wire which is mounted in the channel 17 and has its end portion lying alongside of the upper end of the barrel. By this method is facilitated the assembling 85 of the device, the coil being mounted on the barrel from below and the straight upper part of the coil is threaded or inserted in the channel 17, with little effort. A band 18 is mounted around the upper end portion of the barrel 11 and contacts with the exposed terminal of the coil 16. The band is secured by a screw 19, which also serves for the connection to said 90 band of a conductor 20, which is a part of the ignition circuit. The lower end of the coil, which is thus in the ignition circuit, acts as one of the electrodes, and with the electrode 14 forms the gap for the jump 100 spark to ignite the charge. In addition to this function the coil, which extends the entire length of the chamber of the shell 10, causes the production of an abnormal amount of heat in the spark plug chamber, 105 to super-heat the charge of fuel gas in the plug and cylinder head, just prior to the moment of ignition, thus greatly facilitating the ignition process. This heat, applied to the fuel gas at the place of ignition, 110

and just prior thereto, has been found to be much more effective than any method of heating the fuel at a place remote from the place of ignition, such as in the manifold. 5 This heating through the resistance coil 16 also has the effect of burning off and removing any quantity of soot or carbon dust which may have collected on and around the electrodes, or in the chamber of the shell 10, and this result takes place at the time of 10 firing so that the collection of carbon is prevented. Thus the power and efficiency of the engine is increased by the easy and sure firing of the charge of fuel.

15 The coil 16 is exposed throughout the length of the chamber of the shell 10, and throughout the lower tapered length of the barrel 11, and is effective throughout its entire coiled portion in radiating heat to the 20 surrounding parts, and to the fuel gas in the chamber and adjacent thereto, and in burning off any incipient deposits of carbon or soot before they have accumulated to the extent of causing any loss of efficiency in the 25 device.

I claim as my invention—

A spark plug, comprising a shell formed with a chamber, an insulated barrel fitted in its central portion to said shell and tapered

both above and below said central portion, 30 an electrode extending longitudinally of said barrel and projecting at its lower end therefrom, a coil mounted around and exposed throughout the length of the tapered lower end portion of said barrel and also encircling 35 but spaced and separated from the projecting lower end of said electrode, with which said coil cooperates as a second electrode, the lower end of said second electrode being also secured to said shell, the insulated barrel being formed with a straight 40 channel extending upwardly from the top of its lower tapered portion to an intermediate part of its upper tapered portion, said coil or second electrode being formed with a 45 straight upper portion seated in said channel and passing out of the upper tapered portion of said barrel, a contact member secured to said barrel in contact with the exposed upper portion of said second electrode, 50 and a conductor secured to said contact member.

Signed by me at Des Moines, Iowa, in the presence of two witnesses.
